UNITED STATES PATENT OFFICE.

BENJAMIN T. WELLS, OF BOSTON, MASSACHUSETTS.

DESIGN FOR A CAMPAIGN-CLOAK.

SPECIFICATION forming part of **Design No. 11,974**, dated **October 5, 1880.**

Application filed July 10, 1880. Term of patent 3½ years.

To all whom it may concern:

Be it known that I, BENJAMIN T. WELLS, a citizen of the United States, residing at Boston, in the county of Suffolk and State of Massachusetts, have invented and produced a new and original Design for Improvement in Campaign-Cloaks, of which the following is a specification, reference being had to the accompanying drawing, forming part thereof.

10 The drawing represents a view of my campaign cloak or cape spread out.

I am aware that cloaks or capes have been made heretofore in this general shape and of all colors.

15 The distinctive feature of my design consists in impressing upon the front and back of the

cape or cloak a design representing a gold dollar. This may be either printed or embossed and gilded, the idea being to produce a campaign cloak or cape having emblazoned upon it, very much enlarged, representations of a gold dollar.

I claim—

The design for a campaign cloak or cape herein shown and described, the same consisting of the garment A A, having upon it the emblazoned representations B B B of a gold dollar.

BENJAMIN T. WELLS.
